UNITED STATES PATENT OFFICE.

HARRY J. HANKEE, OF MINNEAPOLIS, MINNESOTA.

TRAFFIC-SIGNAL FOR AUTOS.

1,327,671.

Specification of Letters Patent. Patented Jan. 13, 1920.

Application filed March 14, 1919. Serial No. 282,613.

To all whom it may concern:

Be it known that I, HARRY J. HANKEE, citizen of the United States, residing at Minneapolis, in the county of Hennepin and State of Minnesota, have invented certain new and useful Improvements in Traffic-Signals for Autos; and I do hereby declare the following to be a full, clear, and exact description of the invention, such as 10 will enable others skilled in the art to which it appertains to make and use the same.

Broadly, my invention provides an extremely simple and highly efficient improvement in electromagnetic devices for producing vibratory motion. It involves the use of a field magnet or magnets and a coöperative armature or armatures combined with a so-called full stroke device in the nature of a cam subject to a spring in one direction 20 and adapted to be electrically moved against a spring in the opposite direction. More than the first half of the vibratory movement is produced by the energy of the electromagnet or magnets and resulting 25 momentum of the part moved, and the remaining portion of the vibratory movement is produced by the spring acting on the cam devices.

The vibratory movement will usually be 30 an oscillatory movement on the axis that is concentric with the axis of the moving armature or armatures; and usually the field magnet or magnets will be fixed and the armature or armatures will be movable. A 35 device of this character may be put to a large number of different uses. It is exceedingly well adapted for use in moving traffic signals on automobiles or for moving the reflectors of headlights to vary the 40 projection of a light beam on the road.

A commercial form of the invention is illustrated in the accompanying drawings wherein like characters indicate like parts throughout the several views.

45 Referring to the drawing;

Figure 1 is a perspective view showing the invention incorporated in a traffic signal on an automobile;

Fig. 2 is a wiring diagram for two signals 50 located, one on each side of the automobile;

Fig. 3 is a rear elevation of the traffic signal shown in Fig. 1;

Fig. 4 is a plan view of the parts shown in 55 Fig. 3, some parts being sectioned;

Figs. 5, 6 and 7 are enlarged sections taken through the electromagnetical motion

devices of the traffic signal approximately on the line 5-7 of Fig. 4, but illustrating different positions of the armatures and semaphore;

Figs. 5^a, 6^a and 6^b are views of the parts shown singly in Figs. 5 and 6, with the casting and certain other parts sectioned, but with the field magnets and some other parts in full;

Figs. 5^b, 6^c, 6^d and 7^a are detail views showing the relation of a so-called full stroke cam and coöperating cam pin when the parts are, respectively, in the position shown in Figs. 5, 6 and 7.

Fig. 8 is a perspective view with some parts sectioned and some parts broken away, showing the field magnets, the movable armature, semaphore arm, and coöperating cam and cam pin;

Fig. 9 is a vertical section showing the electro-magnetical motion device applied to vibrate or oscillate the reflector of the headlight; and

Fig. 10 is a wiring diagram for two 80 headlights, as arranged on an automobile.

The arrangement illustrated in Figs. 1 to 8 inclusive, will first be described. Referring first to Fig. 1, it is only necessary to note that the traffic signal is shown as 85 applied to one side of the wind-shield frame and is electrically connected to a push-button 12 on the steering wheel. The diagram view, Fig. 2, shows the wiring for two traffic signals applied, as stated, one to each side 90 of the wind-shield frame and each operated by its own push button 12. To support the semaphore and electro-magnetical motion devices from the wind shield frame, as stated, I have shown a tubular arm 13 provided at its inner end with a suitable clamp 14 for direct connection to said frame 11. To the outer end of the arm 13, is secured an elbow coupling 15 to which a laterally projecting spindle 16 is rigidly secured. It 95 should be remembered that this spindle is fixed so that it cannot rotate.

As shown, and preferably, I employ three field magnets 17 which, at their inner ends, are rigidly secured to the fixed 105 spindle 16 and project radially therefrom at angles of one hundred and twenty degrees. The spindle 16 is of brass or other non-magnetic metal, so that the magnetic field circuit is not extended through the 110 said spindle.

For coöperation with the outer pole of

each field magnet 17, there is an armature 18, the said armatures being also spaced so that their radial medial lines are 120 degrees apart. These armatures 18 have cylindrical surfaces and they are spaced so that they move close to but slightly out of clearance with the outer poles 17^a of the coöperating magnets 17. The armatures 18 are of wrought iron or of soft steel, and preferably 10 they are formed as lateral projections of a common armature plate 19. The extended ends of the armatures 18 are connected by a three-arm bearing plate 20. At the axis of the curve of the armatures 18, the armature 15 plate 19 and bearing plate 20 have axial perforations through which the fixed spindle 16 is passed, so that the complete armature structure is made to vibrate or oscillate on the said spindle.

20 By reference particularly to Figs. 5^a, 6^a and 6^b, it will be noted that the inner ends of the magnets 17 are rigidly and directly secured to an iron or soft steel sleeve 21 that is pinned, or otherwise rigidly secured to the 25 spindle. The spindle 16 has a reduced outer end 16^a that extends some distance into the sleeve 21, so as to afford a seat for the coiled spring 22. That end of the sleeve 21 that is at the left, in respect to Figs. 5^a, 6^a and 6^b, 30 is preferably formed with an outstanding flange 21^a which extends the surface of the common field pole, assisted by that end of the sleeve 21. A thin non-magnetic washer 23 is placed on the reduced end 16^a of the 35 spindle, and by the spring 22 is pressed against the common armature plate 19. It should now be noted that the entire armature structure is not only mounted on the spindle for vibratory or oscillatory movements, but is free for lateral or axial movements.

The spindle 16, between the bearing plate 20 and the adjacent sides of the electromagnets, is provided with a rigidly secured 45 radially projecting cam pin 24 that coöperates with a V-shaped cam 25 that is formed as a part of, or otherwise rigidly secured to, said bearing plate 20 and extends concentrically to the axis of the spindle 16. At 50 the extremities of this cam surface, cam 25 is preferably formed with cam seating depressions 26, the apex of said cam being midway between these depressions. Just beyond said depressions 26, the plate 20 is provided with 55 cam stops 27. The numeral 28^a indicates the motor-casing.

The numeral 28 indicates a semaphore arm rigidly attached to and radially projecting from one of the armatures 18 and 60 provided at its outer end with a small lamp housing 29, preferably V-shaped in formation, and containing an electric lamp, not shown, and not necessary for the purpose of this case, to further consider.

65 Connected to and projecting radially from

the other two armatures 18, in axial line with the arm 28, is an arm counterbalancing weight 30.

In the diagram view, Fig. 2, the numeral 31 indicates a light bulb that may be placed 70 in the lamp housings 29 of the semaphore arm 28, and it will be understood that the said housing will have transparent front and rear plates, one of which, may be red and the other green, as usually required by traffic 75 laws. The numeral 32 indicates the batteries or source of electrical energy which may be, and preferably is, a storage battery carried by the automobile.

The numeral 33 indicates leads from the 80 battery 32 that are connected through the coils of the field magnets 17. The divided circuit for each signal will have a switch which is preferably and as already noted, a push-button 12 on the steering-wheel. The 85 bulbs 31 are connected in shunts 33' across the respective motor circuits 33 and these shunts are provided with switches 34, said switches preferably being incorporated into the signal so as to coöperate with the moving 90 armatures and place the light bulbs in circuit only when the semaphore arms are in a signaling position.

The closing of a field circuit by means of a push-button 12 will cause the corresponding field magnets 17 to be energized. It should, of course, be understood that the field magnets 17 of the motor are electrically connected in such a manner that when energized, the outer tips of the field poles 100 become like magnetic poles, while the flanged end 21^a of the steel sleeve 21, becomes the unlike common pole of the whole magnetic system. For convenience, assume that the multiple armature 18-19 is in its normal 105 position in Figs. 1, 3 and 5, this being the neutral or upright position of the semaphore. In this normal position, the armature and semaphore are held by the engagement of one of the cam depressions 26 with 110 a fixed cam pin 24 (see particularly Fig. 5^b) under action of the spring 22. In this normal position, the magnetic circuit is through the field poles, across the air gap to the armature faces, thence through the steel plate 115 19 of the armature and through the air gap and flanged end 21^a and body of the steel sleeve 21 to the pole pieces.

Obviously, closing of the field motor circuit, as just described, will magnetically energize such field, as stated, and due to the high permeability of the steel in the magnetic circuit, as compared with that of the air, the magnetic field will exert forces in the direction of its flux lines, and chiefly to decrease the reluctance of the magnetic circuit by decreasing the air gap portion of the circuit. Thus, a torque is exerted on the armature in the direction of the arrow (Fig. 5), and this torque exerts a force to move the 120 125 130

semaphore arm in a direction from that shown by full lines toward that shown by dotted lines in Figs. 3 and 6. Also, and at the instant a like force will attract the armature plate 19 in a direction parallel to the axis of the spindle 16, and this force will move the armature on that line in a position from that shown in Fig. 5^a to the one shown in Fig. 6^a; and this latter movement of the armature releases the cam 25 from the fixed cam pin 24, so that the oscillatory movement produced by the torque is free to throw the armature and semaphore arm from the position shown by full lines Figs. 3 and 5, nearly to the position shown in Fig. 6. The momentum will insure such movement to or slightly beyond the position shown in Fig. 6, and if the circuit be not immediately broken, the armature will assume the position shown in Fig. 6. In the position shown in Fig. 6, the apex of cam 25 in the direction of the arrows, Figs. 5, 6 and 7, is carried slightly beyond fixed cam pin 24, or to a position shown in Fig. 6^c. Fig. 6^d, shows the position of the cam-pin and cam after the parts have been thrown in position shown in Fig. 6^c, but just after the field circuit has been broken. When the cam, by the action of spring 22 is thrown against fixed cam pin 24, as shown in Fig. 6^d, the force of said spring, acting on said cam and cam pin, will complete the movement of the armature and semaphore in the direction just noted and cause the said cam and armature to assume the position shown in Fig. 7 in which position the armature will then stand, as shown by dotted lines in Fig. 3 and the full lines in Fig. 7. Thus it is seen how the spring actuated cam device operates as a full stroke device, to insure the final and complete movement of the armature and semaphore, and that the cam seating depressions 26 provide a latching device at the completions of said movement.

When the armature stands in the position shown in Fig. 7, it is in a similar but just reverse relation to that shown in Fig. 5, so that when the motor circuit is again closed, the action already described will be repeated in a reverse order and the armature and semaphore will be again returned to the normal position shown in Figs. 1, 3 and 5.

Fig. 4 shows the manner in which the field leads 33, which are contained in an insulating casing 33^a, are brought in through the tubular arm 13, elbow 15 and spindle 16 to the field magnets 17.

Fig. 9 illustrates the invention applied to oscillate the movable reflector of an automobile headlight. Of the parts of the headlight, the numeral 36^a indicates the casing which will be supported in the usual, or any suitable way. The numeral 35 indicates the lens and the numeral 36 the clamping rim 65 of the headlight. The numeral 37 indicates

the reflector which, at its upper portion, is pivoted to the upper portion of the casing by a hinge 38. The reflector is provided at its axis with the customary socket 39 for holding an electric light bulb 40.

In this application of the motor or electro-mechanical device, the parts thereof, are placed in a supplemental casing 41 secured to the lower back portion of the lamp casing 36^a, and opening thereinto. The spindle 16, 75 is, in this arrangement, rigidly secured to the supplemental casing 41. The armature plate 19 is connected to the lower swinging portion of the back of the reflector 37, by a crank rod 42 and a segmental 80 balancing weight 43, for increasing the inertia and momentum of the armature elements, is secured to one of the armatures 18. The armature elements, when oscillated, will operate in the same manner as described in 85 connection with the semaphore, and its oscillating movements, will, as is obvious, impart oscillatory movements to the reflector. When the reflector is in the full line position, Fig. 9, the light beam will be set for 90 long projection, while when the reflector is set in the dotted line position, the light beam will be thrown upon the ground a short distance ahead of the machine so as to prevent blinding effects.

Fig. 10 is a wiring diagram for two such headlights connected to a car. Switch 44 controls the lamp circuit, while switch 45 controls both motors. Attention is called to the fact that, due to the inherent characteristics of this motor device, two or more may be placed in the same circuit and stay properly synchronized, without further means provided for insuring this uniform action.

From the foregoing, it is evident that this 105 improved electromagnetic motion device, so-called, is capable of a large range of different applications for producing vibratory, that is, reciprocating or oscillatory movements.

Obviously, the device described, is capable of modification in respect to details, and its arrangement of parts. For instance, so far as the broad invention is concerned, either the magnetic element or the armature element may be oscillated, while the other is fixed, and the co-operating cam elements for insuring completion of the movable element and securing of the same at the limits of its movement, may be interchangeably applied; the important thing being that the said cam elements are thrown out of action by the magnetic force, and are thrown into action when the magnets are deenergized.

The statement that the "magnet and armature have outer end poles," means that they are provided with co-acting poles that operate to produce rotation of one of the members in respect to the other, and the statement that they have axial poles means that 125

they have co-acting poles in the vicinity of the axis of oscillation which operate to produce a lateral movement of one of said members in respect to the other.

5. What I claim is:—

1. In an electro-mechanical motion device, the combination with a magnet radiating from the axis of its support, an armature also radiating from the axis of support, said 10 magnet and armature having outer end and axial poles coöperating to produce relative oscillatory and lateral movements when said magnet is energized, the oscillatory member being normally held against but adapted to 15 be free for oscillation by said lateral movement.

2. In an electro-mechanical motion device, the combination with a magnet radiating from the axis of its support, an armature also radiating from the axis of support, said 20 magnet and armature having outer end and axial poles coöperating to produce relative oscillatory and lateral movements when said magnet is energized, and cam elements on 25 said members operative under lateral motion to insure the final part of the oscillatory motion.

3. In an electro-mechanical motion device, the combination with a supporting spindle, 30 of a field magnet supported by and radiating from said spindle, an armature also supported by and radiating from said spindle, one of said spindle supported elements having oscillatory and lateral motion thereof, 35 said magnet and armature having outer end and axial poles coöperating when the field magnet is energized to produce oscillatory and lateral motion in the movable element, the said spindle supporting elements having 40 coöperating spring engaged cam elements for insuring complete oscillatory movements.

4. In an electro-mechanical motion device, the combination with a spindle, of a field magnet rigidly supported by and radiating 45 from said spindle, a normally held armature mounted for oscillatory and lateral movements on said spindle, said magnet and armature having coöperating outer end and axial poles for producing oscillatory and 50 lateral movements of said armature when said field magnet is energized, the lateral movement of said armature serving to free the same for oscillatory movement.

5. In an electro-mechanical motion device, 55 the combination with a spindle, of a field magnet rigidly supported by and radiating from said spindle, an armature mounted for oscillatory and lateral movements on said spindle, said magnet and armature having 60 coöperating outer end and axial poles for producing oscillatory and lateral movements of said armature when said field magnet is energized, a reversely beveled cam movable with said armature, a coöperating cam-pin 65 fixed in respect to said magnet, and a spring

tending to press said cam and cam-pin into contact, to cause the same to complete the oscillatory movements of said armature.

6. In an electro-mechanical motion device, the combination with a magnet radiating 70 from the axis of its support, an armature also radiating from the axis of support, said magnet and armature having outer end and axial poles coöperating to produce relative oscillatory and lateral movements when said 75 magnet is energized, and yielding means for holding the movable element in extreme positions but arranged to be released by such lateral movement.

7. In an electro-mechanical motion device, 80 the combination with a magnet radiating from the axis of its support, an armature also radiating from the axis of support, said magnet and armature having outer end and axial poles coöperating to produce relative 85 oscillatory and lateral movements when said magnet is energized, yielding means for holding the movable element in extreme positions, said means comprising an approximately V-shaped cam flange on one of the 90 members, a cam projection on the other of said members, and a spring tending to hold said cam flange and pin in engagement.

8. In an electro-mechanical motion device, the combination with a plurality of radially 95 disposed, circumferentially spaced, relatively fixed magnets, having outer end poles and a common axial pole, of a coöperating pivotally and laterally movable armature having outer end poles for coöperation with the 100 outer end poles of said magnets, and having a common axial pole for coöperation with the common axial magnetic pole, whereby when said magnets are energized, said armature will be moved laterally and released and 105 then oscillated.

9. In an electro-mechanical motion device, the combination with a plurality of radially disposed, circumferentially spaced, relatively fixed magnets, having outer end poles 110 and a common axial pole, of a coöperating pivotally and laterally movable armature having outer end poles for coöperation with the outer end poles of said magnets, and having a common axial pole for coöperation 115 with the common axial magnetic pole, said armature being normally held against oscillation but arranged to be released for oscillation by said lateral motion, whereby when said magnets are energized, said armature 120 will be oscillated and moved laterally, and yielding means for holding said armature in extreme positions.

10. In an electro-mechanical motion device, the combination with a plurality of radially disposed, circumferentially spaced, relatively fixed magnets, having outer end poles and a common axial pole, of a coöperating pivotally and laterally movable armature having outer end poles for coöperation 125 130

with the outer end poles of said magnets, and having a common axial pole for coöperation with the common axial magnetic pole, whereby when said magnets are energized, said 5 armature will be oscillated and moved laterally, and coöperating spring pressed cam elements on said magnet and armature elements, operative yieldingly to hold said ar-

mature in extreme positions and to insure completion of its oscillatory movements. 10

In testimony whereof I affix my signature in presence of a witness.

HARRY J. HANKEE.

Witness:

CLARA DEMAREST.
